H. L. WILKENS

PORTABLE LAVATORY

Original Filed Mar. 3, 1921

Inventor
Kerman L. Wilkins
By his Attorney F. J. Parker

UNITED STATES PATENT OFFICE.

HERMAN L. WILKENS, OF RIDGEWOOD, NEW JERSEY; GESINE WILKENS ADMINISTRATRIX OF SAID HERMAN L. WILKENS, DECEASED.

PORTABLE LAVATORY.

Application filed March 3, 1921, Serial No. 449,463. Renewed July 25, 1922. Serial No. 577,491.

To all whom it may concern:

Be it known that I, HERMAN L. WILKENS, a citizen of the United States, and resident of Ridgewood, in the county of Bergen and 5 State of New Jersey, have invented certain new and useful Improvements in Portable Lavatories, of which the following is a specification.

This invention relates to portable lavatories, and my improvements are particularly directed to a folding device which includes a hand wash-basin, a water supply tank, draining means for used water, a receptacle for the elements of a first aid kit, 15 and other useful articles of emergency and sanitary utility.

The entire apparatus, when closed, is in rectangular or suitable form and of such dimensions that it may be conveniently located upon the running board of an automobile, and there opened out for service.

The principal purpose for which my said invention is intended is to enable the motorist to wash his hands after he has performed 20 a repair or adjustment, on the road, or has changed a tire, which facility is frequently desired, but for which no provision is found in present day automobile equipment.

I realize fully that compactness and light 30 weight in an apparatus of this character are essential, and have devised it accordingly, also providing therein the means for dressing wounds which may result from accidents met with on the road.

35 Other features and advantages of my invention will hereinafter appear.

In the drawing:—

Figure 1 is a perspective elevation of the apparatus, open for service.

40 Fig. 2 is a section on the line 2—2 of Fig. 1.

Fig. 3 is a longitudinal section through the folding member of the device, and

45 Fig. 4 is a detail of the faucet and its valve.

Mainly the device consists of the part 1, having flat base 2, by which it is to be placed as upon the running board of an automobile, to which it is to be secured by any suitable means, and the movable part 3 which is 50 hinged, at 4, to said part 1.

Said part 1 includes the vertical rear wall 5, side walls 6, 6, and top 7, said side walls being cut away from their upper forward portions, with a downwardly rearward inclination, as at 7^a, 7^b, to the points 7^b, 7^b, where they continue forwardly in the projecting, lower portions 7^c, 7^c; and the movable part 3 has the front portion 8, that is vertical when closed, top wall 9 and side walls 10, 10. Said side walls are of increasing width toward their base, that they may thereby be guided within the side walls 6, 6 of part 1 in the act of closing the device.

Secured within the upper portion of part 65 1 is a water tank 11, whose ends reach almost to the side walls 6, 6, but leave a slight clearance, for a purpose to be referred to hereinafter. The water tank is shown as connected to rear wall 5 by fastening 11^a. 70

The base of said water tank is elevated a suitable distance above base 2, to provide a clearance therebetween, and also that it may be disposed at an elevation relatively to the part 3, when the latter is open, for the 75 service flow of water from said tank; because said part 3 includes a wash basin which is to be supplied with water from said tank.

Said basin, indicated at 12, is sunk in the 80 inner portion of part 3, which inner portion, when part 3 is opened out, becomes then its upper portion, and, in describing said part 3 as opened out, it has a top plate of frame 13, that is sunk below the upper edges of 85 walls 9 and 10, 10, so that water splashing upon the plate 13 will be confined thereon, while said part 3 is extended in its own position.

Plate 13, at the rear of the wash basin, 90 is provided with a curved guard 14, and a waste outlet 15 extends partly through said guard and partly through the upper rear portion of the basin, so that, when the basin is to be emptied, by folding up part 3 into 95 or against part 1, the waste water will flow through said outlet into the lower portion of part 1, whose surface, 16, is centeringly inclined to a drain orifice 17, for discharge, said surface having inturned lip edges 16^a 100 to confine waste water poured thereon.

In this folding up action of part 3, to

discharge waste water from the basin, the guard 14 serves as a collector trough to guide the flow of water into the outlet 15.

A horizontally disposed faucet 18 is pivotally mounted in the base of the water tank, where it is provided with a valve 19, having an oval orifice, whose greatest dimension extends vertically, to open when the faucet has been swung out over the basin, and to close during the first part of the rearward swinging movement given the faucet. This is so that the flow of water to the basin shall not begin until the faucet has been swung out far enough for it to supply the basin, and shall shut off in the beginning of the swing back movement given the faucet.

The upper surface of part 3 (referring thereto in its open position) is inclined downwardly forward at the same angle as its side walls 10, 10, so that if its base were to lie in the same plane as base 2 the upper perimeter of the basin would be at a forwardly downward angle, but I provide means for supporting the part 3 with its upper surface in a level plane. These means comprise the slotted, arcuate arms 20, 20, pivoted as at 21 to the walls 10, 10, and engaging by means of their slots with studs 22 located near the forward edges of side walls 6, 6, the arrangement being such that said arms, when fully extended, co-act with said studs 22, which serve as stops causing said arms to hold the part 3 suspended with its upper surface in a level plane.

The part 3 being hollow is useful as a container for bandages, plasters, salves, and other articles comprising a first aid or emergency kit. Said part 3 is provided with the covers 23, 24, each hinged at 25 to the plate 13, and having their front edges in engageable relation. Thus, the cover 23 has an upturned forward edge 26, which co-acts with the upper edges of walls 9 and 10 to prevent water splashed upon said cover from running off the top of part 3, and also prevents water from entering the covered receptacle; and the covers 24, for similar purposes, have the looped edge 27 that fits over edge 26.

The clearances between side walls 6 and the ends of water tank 11 are intended to admit the entrance of the forward edges of walls 10, and also to receive the arcuate arms 20 in the closing action of part 3.

An aperture 28 provided in a depressed portion of cover 7 is intended as a filling orifice for the water tank, which is provided with an orifice 29 in alignment therewith, a screw stopper 30 serving to close both said aperture and orifice. Said stopper lying within the said depressed portion aforesaid, so that a cover 31, hinged at 32 to part 1, may close snugly down upon top 7. Said cover 31 is of sufficient extent to lie over the entire top of the apparatus when the part 3 is folded up against part 1, and said cover

is provided with hasps 33 to engage in sockets 34 upon part 1 to effect an engaged closure.

Guarded depressions 35, 36, are provided upon plate 13 for the reception of soap and nail-brush respectively.

It should be noted that the edges of the plate 13 to which the covers 23, 24 are hinged, have down-turned flanges that prevent the passage of water through the hinges, and that the covers themselves have up-turned flanges lying over said down-turned flanges, for the same purpose.

Variations within the spirit and scope of my invention are equally comprehended herein by virtue of the foregoing disclosure.

I claim:—

1. A portable lavatory comprising a casing having a rear wall, side walls and an open front, a water tank contained in the upper portion of said casing within the confines of its side walls, a closure element hinged to fold upwardly against said front, a wash basin carried by said closure element, means for conveying water from said tank to said basin when the closure element is open to present the basin in usable position, a rear splash guard for said basin, means for the discharge of water from said basin into the casing bottom as said closure element folds back, and discharge means for said casing bottom.

2. In a portable lavatory, in combination, a casing having a rear wall, side walls and an open front, a water tank contained in the upper portion of said casing within the confines of its side walls, with clearances between its ends and the side walls of said casing, a closure element hinged to fold upwardly against said front, arcuate, slotted arms, having guide means, engaged with the sides of said closure element, and adapted to pass into said clearances in the closing movement of said closure element, said guide means also serving as stops to limit the opening movement of said closure element, and to suspend it when open, a wash bowl in said closure element, and means for conveying water from said tank to said bowl, when the closure element is open to present the basin in usable position.

3. In a portable lavatory, in combination, a casing having a rear wall, side walls and an open front, a water tank contained in the upper portion of said casing within the compass of its side walls, a closure element hinged to fold upwardly against said front, a wash basin sunk within said closure element, means for conveying water from said tank to said basin, a receptacle in said closure element, a hinged cover for said receptacle, and means for preventing water splashed out of said basin, upon the said hinged cover, from entering said receptacle.

4. In a portable lavatory, in combination,

a casing having an open front, a water tank contained in the upper portion thereof, a closure element hinged to fold against said front, a wash basin carried by said closure element, means for conveying water from said tank to said basin, and a top cover, hinged to said casing and adapted to enclose the top of said closure element, with the top

of said casing, when said closure element is folded against said front.

Signed at the borough of Manhattan, in the city and county New York and State of New York, this 21st day of February, A. D. 1921.

HERMAN L. WILKENS.
